US0D1042831S

(12) **United States Design Patent** (10) **Patent No.:** **US D1,042,831 S**
(45) **Date of Patent:** **** Sep. 17, 2024**

(54) **SUTURE ANCHOR**

(71) Applicant: **Anika Therapeutics, Inc.**, Bedford, MA (US)

(72) Inventors: **Greg Denham**, Lakewood Ranch, FL (US); **Joel Harshbarger**, Palmetto, FL (US); **Adrian Bosworth**, Bradenton, FL (US)

(73) Assignee: **Anika Therapeutics, Inc.**, Bedford, MA (US)

(**) Term: **15 Years**

(21) Appl. No.: **29/912,464**

(22) Filed: **Sep. 19, 2023**

Related U.S. Application Data

(63) Continuation of application No. 29/853,422, filed on Sep. 15, 2022, which is a continuation of application No. 17/892,796, filed on Aug. 22, 2022.

(57) **CLAIM**

We claim the ornamental design for a suture anchor, as shown and described.

DESCRIPTION

FIG. 1 is a top perspective view of a suture anchor; FIG. 2 is a bottom perspective view thereof; FIG. 3 is a front elevation view thereof; FIG. 4 is a rear elevation view thereof; FIG. 5 is a top plan view thereof; and, FIG. 6 is a bottom plan view thereof. The broken lines in the drawings illustrate portions of the suture anchor and form no part of the claimed design.
